CLAIM

The ornamental design for a sun sleeve as shown and described.

DESCRIPTION

FIG. 1 is a first perspective view of the sun sleeve design within a user environment;

FIG. 2 is a second perspective, close up view of an upper portion of the sun sleeve design;

FIG. 3 is a back view of the sun sleeve design;

FIG. 4 is a front view thereof;

FIG. 5 is a first side view thereof;

FIG. 6 is a second side view thereof;

FIG. 7 is a bottom view thereof; and,

FIG. 8 is a top view thereof.

The dotted lines depict environmental portions that form no part of the claimed design. The dash-dot lines depict stitching that forms no part of the claimed design.

1 Claim, 5 Drawing Sheets
